United States Patent Office.

GEORGE HOOVER AND A. N. HADLEY, OF RICHMOND, INDIANA.

Letters Patent No. 60,728, dated January 1, 1867.

IMPROVEMENT IN MACHINES FOR SPINNING, TWISTING, AND REELING.

The Schedule referred to in these Letters Patent and making part of the same.

TO WHOM IT MAY CONCERN:

Be it known that we, GEORGE HOOVER and ARTEMUS HADLEY, of Richmond, Indiana, have invented certain new and useful improvements in Spinning, Twisting, and Reeling Machines; and do hereby declare the following to be a full, clear, and exact description of the same, reference being had to the drawings which accompany this specification, forming a part thereof; and to the letters of reference which are marked thereon. In the drawings—

Figure 1 is a front elevation of our machine.

Figure 2 is an end elevation.

Figure 3 is a transverse vertical section of the upper portion of the machine, taken at the red line *z z*.

Figure 4 is a top view of the clove-clamp or sash.

Like letters refer to like parts.

Our invention consists in an arrangement and combination of mechanical devices, consolidated in a single machine, by which we produce a spinning, twisting, and reeling machine, operated by hand, simple in its construction and effective in its operation.

In fig. 1, *a a a a* represent the framing, which is of ordinary form. The driving-wheel, *b*, revolves on the shaft, *m*, fig. 2, to which a handle is attached to put it in motion, and is secured across the end of the frame in suitable bearings. The pulley, *c*, upon the opposite end of the frame, revolves upon a shaft, secured in a similar manner. Across the upper portion of the frame are parallel bars, *H H*, provided with holes a suitable distance apart, into which are inserted spindles, *i i i i*, &c. Each of these spindles is provided with a pulley rigidly attached; the outer edges of which are grooved to receive a driving-cord, the spindle terminating in a point, and of sufficient length to receive and revolve a bobbin. The friction-pulleys, *e e e e*, are attached to the upper cross-piece of the framing at points between the spindle-pulleys, and extend downward to a line below the level of the upper surfaces of the spindle-pulleys, their circumferences being provided with a groove similar to the spindle-pulleys, for the purpose of receiving the driving-cord, and they are intended to press the driving-cord upon the spindle-pulleys to a degree sufficient to insure their revolutions. The shaft, *F*, is placed across the upper portion of the framing, with suitable bearings, and is provided with a fly or flier wire, *j j*, which is operated by the partial revolutions of the shaft *F*. The spring *F'* operates the shaft *F*, and serves to hold the fly *j j* up against the plate *H*. Upon the outside of the frame is a crank-lever, *O*, which operates the shaft *F*, as seen in fig. 2, where *p* represents a spring-trigger operated by the cord *q*. *A* is a sliding sash or clamp-clove, having a vertical motion and working upon the guides *h h*, by means of eyes or loops in the ends of the same. The sash is provided with a handle, *B*, by means of which the operator raises and lowers the sash in the process of spinning. *C* is a cam lever, the cam of which works against the post of the handle, and serves to open the jaws of the sash to allow the free passage of the roving for the succeeding threads, the jaws being closed by the action of the spring *A'*, fig. 3. The weights, *f f'*, are counterbalances to the sash, and are suspended by the cords, *g g*. Upon the top of the sash are placed bobbins, *k k'*, from two or more of which the threads may be twisted, as shown at fig. 1, by the dotted lines. One end of the sash *A* is provided with a curved arm *a'*, fig. 3, which serves to bring the fly forward during the act of spinning, and it is thus held in position until the thread is sufficiently twisted, when by the upward action of the sash the rod *q* releases the bent crank-lever *O*, the fly *j j* is brought back to the bar *H*, and the yarn is thus carried back to the but of the bobbin and wound up, when the curved arm *a'* brings the fly *j j* out to the front of the spindles far enough to again lock or detain by crank *O* and spring *p*, where it remains until it is released by the upward motion of the sash *A* acting upon the rod *q*. The spur-wheel *d* is secured to the shaft *n*, upon which it revolves, being operated by a single cog upon the shaft *m*, of the driving-wheel *b*, producing one revolution of the cog or spur-wheel *d*, to every sixty revolutions of the driving-wheel *b*. A projection upon the centre of the outside of the spur-wheel *d* is provided with a single recess into which a click-spring, *I*, works, giving warning of the completion of each cut in reeling. *G* is a rolls-shaft, placed lengthwise of the framing in the central portion shown, and near the bottom, revolving upon suitable bearings, a number of endless rolls equal to the number of spindles being placed herein for use. The functions of the rolls-shaft *G* consist in its being the shaft or journal upon which the rovings are wound separately of any desired length, and in number equal to the number of threads to be spun, and which turns upon

its axis when actuated by the stress of the said rovings, when operated by the jaw A². These rovings are termed endless as contradistinguished from the ordinary sheet-rolls, they being susceptible of being wound upon the rolls-shaft of any desired length. The hinges D D, fig. 4, connect the sash A and jaw A², and produce a parallel motion of the jaw as it is opened and shut by the operation of the cam lever C. E', the driving-belt or cord, passes from the driving-wheel b to the pulley c, when a second belt or cord, E, passes from the pulley c to the pulley i, as shown by the dotted lines fig. 1. This belt or cord, E E E, passes between the line of spindle-pulleys and the line of pressure-pulleys, fitting into the grooves in each and imparting motion to the former by means of the pressure exerted by the latter; said pulley, c, being adjustable by means of a slot in the framing when the journal of said pulley is secured by a screw-bolt, so that said driving-belts or cords, E and E', can be made tight or loose as occasion requires. By this arrangement we produce a uniform motion of any requisite number of spindles in line by a single driving-belt. It will be seen that our use of the spindle is simply as a stem for the bobbin, and that the twisting and winding of the thread, or in other words the spinning and the winding up of the same, are performed by and upon the bobbin directly instead of the spindle, the spindle for this purpose being of such length as not to project beyond the end of the bobbin.

What we claim as new, and desire to secure by Letters Patent, is—

The arrangement and combination of the mechanical devices herein set forth and described for producing a spinning, twisting, and reeling machine, substantially as set forth and for the purposes described

GEO. HOOVER,
ARTEMUS N. HADLEY.
